UNITED STATES PATENT OFFICE

EWALD F. TECHMER, OF CHICAGO, ILLINOIS, ASSIGNOR, BY MESNE ASSIGNMENTS, TO
NATIONAL KELLASTONE COMPANY, OF CHICAGO, ILLINOIS, A CORPORATION OF
DELAWARE

WALL CONSTRUCTION

Application filed July 26, 1928. Serial No. 295,593.

The present invention relates to wall construction and is particularly concerned with the construction of interior walls or partitions.

5 In the construction of partitions for apartments, office buildings and the like, it has been customary to build up the wall proper of tile, brick or some other core, after which it is necessary to secure furring strips along 10 the bottom of the wall for use as a ground in plastering and for securing the baseboards to the wall.

One of the objects of the present invention is the provision of an improved base block 15 construction for walls of the class described, whereby the necessity for furring strips is eliminated, the base block itself being capable of serving as a ground in plastering and as a baseboard if desired.

20 Another object is the provision of a novel base block for partitions which is molded from an initially plastic cementitious material capable of being sawed, chiseled or nailed by means of ordinary tools, thereby making 25 the base block adaptable to any of the conditions usually encountered in the installation of a wall.

Another object is the provision of a novel 30 base block composition which comprises a fireproof cementitious material composed principally of magnesium oxide, magnesium chloride and wood filler such as sawdust, which may be nailed, or sawed by means of a carpenter's saw or chiseled with wood chisels 35 in order to fit the block into any given space without seriously affecting the cutting edges of the tools.

Another object is the provision of a novel 40 base block construction which permits the thickening of a wall where necessary, to pass around pipes imperfectly aligned within the wall space, the plaster ground being automatically located with reference to the thickened wall.

45 Another object is the provision of a base

block of novel shape having an inwardly sloping bearing surface whereby the major portion of the weight is carried by the outer wall of the base block.

50 Other objects and advantages of the invention will be apparent from the following description and from the accompanying drawing, in which similar characters of reference indicate similar parts throughout the several views.

55 Referring to the drawing, of which there is one sheet:

Fig. 1 is a view in perspective of a portion of a wall, including my improved base block;

56 Fig. 2 is a similar view showing the mode of installation of the base block about pipes;

60 Fig. 3 is a plan view of a portion of the wall in partial section, showing the mode of "faking" or thickening the wall where the pipes are out of alignment, a condition which is frequently encountered in actual practice;

65 Fig. 4 is an end view of a modified form of my base block.

70 Referring to Fig. 1, 10 indicates one of my base blocks in its entirety, including the two similar parts or halves 11 and 12. The base block is preferably, but not necessarily, formed with a hollow interior 13 in order to save material, and to provide a dead air 75 chamber which increases the sound insulating qualities of the base blocks, and the block is constructed by molding the same of an initially plastic cementitious material having the requisite qualities outlined hereinafter.

80 One of the most important qualities of my base block is the quality of being severable by means of ordinary tools such as carpenter's saws or wood chisels, and the quality of permitting the driving of nails into or through the block without splitting or breaking the block. This latter quality is notably absent in cementitious materials, but by using the composition hereinafter described, I am 85 enabled to provide a base block which may be nailed in place and in which the nails will 90

be retained much better than is the case with ordinary soft woods.

At the same time, the block molded from such composition is fireproof, soundproof and it may readily be cut into any shape to fit the block about pipes, between the door frames or in other limited spaces encountered in the construction of a wall.

My block is preferably constructed of magnesium oxychloride and wood filler, the former element being formed by the combination of magnesium chloride and magnesium oxide with sufficient water to combine these elements.

A characteristic formula by volume, of one composition of matter having the foregoing qualities, is as follows:

	Per cent
Asbestos	10
20 Magnesium oxide approx	25
Magnesium chloride approx	15
Wood or other filler	50

The foregoing elements are mixed with sufficient water to combine the magnesium oxide and magnesium chloride, forming magnesium oxychloride, and among the various fillers which may be employed are wood, straw, cork, and other fibrous materials.

Referring to the drawing, 14 indicates the base of the flooring 15, the blocks 11 and 12 being preferably disposed upon the floor base to form the bottom of the partition wall indicated in its entirety at 16.

Each of the blocks 11 and 12 may be similar in form, the blocks being oppositely disposed to form a base block capable of supporting the wall core 17 and forming plaster grounds 18 as well as the baseboard 19.

As the blocks 11 and 12 are identical, the description of one of these blocks will suffice, and each block is formed with an outer flat surface 19 which may constitute the baseboard of the finished wall. The block is substantially U-shaped in cross-section, having an inwardly extending flange 20 at its base and a similar flange 21 at its top. The bottom 22 of the flange 20 may be substantially flat to provide support for the block and the flange 20 may be tapered in thickness toward its inner edge 23. The upper flange 21 is also preferably tapered in thickness toward its inner edge 24 and the upper surface 25 slopes downward at a slight angle to the horizontal for a purpose further to be described.

The upper bearing surface 25 is bounded by an upwardly extending shoulder 26 terminating in a flat upper surface 27 adapted to engage the plaster coat 28. The width of the surface 27 is substantially equal to the thickness of the plaster coat to be applied to the wall core 17. The surface 18 extending transversely to the surface 27 may therefore serve as a ground in plastering. Intermediate the ground surface 18 and the baseboard

19, the blocks may be provided with molding or with a shoulder 29 simulating the top of the baseboard.

When the blocks 11 and 12 are oppositely disposed as shown in Figs. 1 and 2, they are 70 adapted to form a base block section having a hollow interior 13 and having an upper bearing surface 25, both sides of which slope toward the center. The wall core 17 being provided with an ordinary flat lower bearing 75 surface, the wall core will be supported for the major part at the outer portions of the surface 25 adjacent the shoulder 26, thereby placing the major portion of the weight of the wall upon the outer part of the base 80 block instead of upon the flanges 20 and 21.

The shoulders 26 are adapted to serve as means for aligning a core above the base block and the shoulders 18 automatically locate grounds for plastering in the proper 85 position.

Referring to Fig. 2, it will be observed that ordinary gas, water and soil pipes may readily be surrounded by my base block sections by cutting notches 30 and 31 in the 90 flanges 20 and 21. By constructing my base block of two sections, I am enabled to fit the blocks adjacent pipes at any point within the length of the block without cutting off the block and without cutting elongated slots 95 extending from the end of the block.

Referring to Fig. 3, I have here illustrated a condition which frequently arises in the construction of partitions or interior walls.

The soil pipe 32 in Fig. 3 has been located either by necessity or through careless work at such a point that it would ordinarily project from the outer surface of the wall if the wall were of normal thickness and constructed in the ordinary manner. In order to "fake" a wall about such projecting pipes, it is customary to apply a thicker coat of plaster or to build up the wall by means of furring strips beneath the laths. As my base block is constructed of two similar sections, this contingency may be readily taken care of by slightly spreading the blocks at such a point, or by uniformly thickening the wall from a corner past the point where the pipe is located, the amount of spread being such that the plaster grounds 18 are substantially outside of the pipe 32. Thus the grounds are automatically located in such position that the pipe 32 will be covered by the plaster coat and the wall will be slightly thickened without the necessity of special work in "faking" the wall about the projecting pipe.

Referring to Fig. 4, I have here illustrated a modified form of my base block in which the entire block is made in one integral piece. This block is likewise provided with the wall core aligning shoulders 26, the inwardly sloping upper bearing surfaces 25, the plaster grounds 18, the plaster coat engaging surfaces 27 and the baseboard surfaces 19. The

block of the present embodiment may also be made hollow as at 13 in order to save material and to provide a dead air space in the block and it will be evident from the foregoing that many of the advantages of my invention may be utilized without incorporating all of the features described herein.

It will thus be observed that I have invented a base block having a novel shape, by means of which much of the labor of the installation of furring strips and baseboards is eliminated. Furthermore, by virtue of the composition of which my base block is formed, it possesses peculiar qualities so that a nail may be readily driven in to the cementitious material of which the block is composed without splitting the block and without forming such a large aperture that the nail will be loose.

20 My block may therefore be nailed in place so that the partition may readily be provided with means for anchoring the wall in place, consisting of a plurality of nails driven through the lower flanges 20 and the 25 blocks may be readily adapted to any space by sawing them off with an ordinary carpenter's saw or by chiseling notches in the blocks to surround pipes, wires or other installations.

30 While I have illustrated and described a specific embodiment of my device, and I have given a specific formula of the composition of matter employed, I do not wish to be limited to the precise details of construction 35 set forth, but desire to avail myself of all changes within the scope of the appended claims.

Having thus described my invention, what I claim is new and desire to secure by Letters 40 Patent of the United States, is:

1. A base block structure molded from initially-plastic cementitious material, and having an upwardly-directed ledge surface of a width to gauge the thickness of a plaster 45 coat thereabove and another bearing surface inwardly thereof at a different level and sloping slightly in.

2. A base block structure molded from initially-plastic cementitious material, comprising two co-acting parts separable to a variable extent, each part having an upwardly-directed ledge surface of a width to gauge the thickness of a plaster coat thereabove and another bearing surface sloping 55 slightly in.

3. A base block structure molded from initially-plastic cementitious material, comprising two coacting parts separable to a variable extent, each part having an upwardly-directed ledge surface of a width to gauge the thickness of a plaster coat thereabove and another bearing surface inwardly thereof at a different level and sloping slightly in.

4. In a wall construction, a molded base block comprising two similar parts oppositely disposed, said block being molded of initially plastic cementitious material of a magnesium compound and fibrous filler, each part having a supporting flange, an upper bearing surface and a ground for plastering whereby the thickness of the wall may compensate for irregularities in alignment of pipes and the like, said upper bearing flange sloping inward to support the major portion of the weight of a wall upon the outer portion of said block.

In witness whereof, I hereunto subscribe my name this 18th day of July, 1928.

EWALD F. TECHMER.
